CLAIM

The ornamental design for a combination teether handle and shield, as shown and described.

DESCRIPTION

FIG. 1 is a top view of a teether handle and shield;

FIG. 2 is a front view thereof;

FIG. 3 is a bottom view thereof;

FIG. 4 is a rear view thereof;

FIG. 5 is a left, side elevation view thereof;

FIG. 6 is a right, side elevation view thereof;

FIG. 7 is a top perspective view thereof; and,

FIG. 8 is a bottom perspective view thereof.

The equal-length broken lines on the surfaces of the combination teether handle and shield depict unclaimed portions thereof and form no part of the claimed design. The equal-length broken lines showing a teether nipple depict environmental structure and form no part of the claimed design. All broken lines form no part of the claimed design.

1 Claim, 8 Drawing Sheets
